UNITED STATES PATENT OFFICE

JAMES H. BODEN, OF ATHENS, OHIO

DESIGN FOR A FLOORING UNIT

Application filed February 24, 1930. Serial No. 34,628. Term of patent 14 years.

To all whom it may concern:

Be it known that I, JAMES H. BODEN, a citizen of the United States, residing at Athens, in the county of Athens and State of Ohio, have invented a new, original, and ornamental Design for a Flooring Unit, of which the following is a specification, reference being had to the accompanying drawing, forming part thereof.

The figure is a perspective view of one of the flooring units forming a part of the floor design.

I claim:

The ornamental design for a flooring unit, as shown.

JAMES H. BODEN.
